O. H. HANSARD ET AL

CONCRETE TESTING APPARATUS

Filed Sept. 1, 1927

UNITED STATES PATENT OFFICE.

ORREN HARDIN HANSARD AND DONALD DAVID MCGUIRE, OF NASHVILLE,
TENNESSEE.

CONCRETE-TESTING APPARATUS.

Application filed September 1, 1927. Serial No. 216,846.

This invention relates to machines for testing concrete and the present application pertains to a second species of the genus described and claimed more broadly in our co-pending application, Serial No. 216,845, filed Sept. 1, 1927. The objects of the invention include the provision of improved apparatus for quickly determining the transverse strength of a concrete block, and reside in the construction of the machine about to be described and defined in the appended claims.

A preferred embodiment of the invention is illustrated in the accompanying drawings, in which, Fig. 1 is a plan view of the improved apparatus with a specimen block of concrete in position to be tested; and Fig. 2 is a side elevation thereof.

The machine is preferably mounted upon a base 3 which may be provided with wheels (not shown) whereby it may be readily transported. A platform 4 mounted upon legs 5 at one end of the base, is provided at one end with a transverse semi-cylindrical block 6 and at its other end with a transverse triangular-shaped member 7 on which the block or beam of concrete 8 is supported with its free end extending a measured distance beyond the knife edge of the member 7. The beam is preferably fastened upon its supports by a bar 9, mounting a semi-cylindrical transverse member 10 on its lower surface, which is secured to a bar 11 passing under the platform by tie bolts 12. Bearing blocks 13, 14 and 15 may be interposed between the member 6, 7, and 10 respectively, and the concrete beam to serve as cushions, and these bearing blocks are preferably provided with longitudinal recesses to receive said member.

A testing lever arm, comprising a V-shaped frame consisting of metal I beam 16 bolted together at the apex of the frame and spaced at their inner ends by a transverse strut 17, is mounted above the projecting position of the concrete beam in such manner that depression of the outer end of the frame will exert a considerable pressure upon the inner end of the beam 8. For this purpose, the frame is supported, intermediate its ends upon the beam end by means of a transverse, triangular shaped bar 18 which is attached to a plate

19 fixed to the under side of the frame and which engages in the recess of a bearing block 20 traversing the top of the beam adjacent its inner end. The frame is fulcrumed near its inner end and approximately above the apex 55 of the member 7 by a cross bar 21 mounted on brackets 22 fixed to the base 3 and provided on its underside with a bearing block 23 which engages a semi-cylindrical transverse member 24 of a plate 25 attached to the top of the 60 frame. The two point support thus holds the lever arm substantially in horizontal position until a downward force is applied at its outer end.

At said end of the lever a rack 26 bolted between the arm end supports the upper loop 27 of the spring of a dynamometer 38 of usual construction and operation. The dynamometer hangs in a vertical plane from the rack 26 and its lower spring loop 28 is attached to a 70 cable 29 by a hook 30. The cable may be wound on a shaft or drum 31 in bearing blocks 32 fixed to the base 3, by means of a crank handle 33 operating through suitable gearing.

Cross bars 34 and 35 supported upon brackets 36 and 37, respectively, may be arranged beneath the frame to catch the lever arm when the concrete beam has been broken in the manner now to be described.

When the apparatus has been set up as thus described, the crank 33 is operated to wind up the cable, thus causing a downward pull upon the outer end of the lever arm through the dynamometer 38, depressing the lever and initiating a downward pressure upon the end of the concrete beam at the bar 18. When the breaking point is reached the concrete beam will fracture transversely above the sharp edge of the member 7 and at that movement a reading of the dynamometer is taken.

The modulus of rupture of the concrete in pounds per square inch may then be obtained mathematically by well known formulæ, after noting the necessary weights and dimensions of the broken off section of concrete and of 95 the lever arm. By utilizing the apparatus herein described, the computation is greatly simplified, for the required weights and dimensions may be maintained constant for repeated tests, so that the only variable factor 100

is the reading of the dynamometer. Hence, after following the formula for the initial test and calculating resultant of the constants, the modulus of any succeeding test may be obtained by multiplying the constant factor by the reading of the instrument.

We claim:

1. Apparatus for testing concrete comprising a platform, means for securing a test piece of concrete upon said platform with one end of the test piece projecting beyond the edge of the platform, a lever extending over the projecting portion of the test piece and having its free outer end extending longitudinally of the test piece and distant from the end thereof, a portion of said lever engaging the upper side of the test piece near the end of said projecting portion, means independent of the test piece engaging the top of the lever adjacent its inner end to prevent movement thereof away from the test piece, means for operating the free end of the lever to break the test piece and a measuring instrument associated with said last named means for indicating the amount of force required to break the test piece.

2. Apparatus for testing concrete comprising a platform, means for securing a test piece of concrete upon said platform with one end of the test piece projecting beyond the edge of the platform, a fixed bracket extending above said platform and having a cross bar disposed above the test piece, a lever extending over the projecting portion of the test piece, the inner end of the lever passing under said cross bar and engaging the bar whereby movement of said lever end away from the test piece is prevented and the free outer end of the lever extending outwardly from the end of the test piece and longitudinally thereof, said lever having a bottom cross member engaging the upper side of the test piece near the end of said projective portion, means for operating the free end of the lever to break the test piece, and a measuring instrument associated with said last named means adapted to indicate the amount of force required to break the test piece.

3. Apparatus for testing concrete comprising a horizontal platform, means for securing a test piece of concrete upon said platform with one end of the test piece projecting beyond the edge of the platform, an upright bracket extending above said platform, a cross bar fixed to said bracket transversely of the test piece and approximately in the plane of the said edge of the platform, a horizontal lever extending longitudinally of the test piece and having its inner end extending over the test piece and under said cross bar, said bar having a bottom transverse member intermediate its ends engaging the upper side of the test piece near the end of its projecting portion and having a top transverse member near its inner end engaging said

cross bar, so that the lever is supported in horizontal position by said engagements, means connected with the free end of the lever for depressing the lever to break the test piece, and a measuring instrument associated with said depressing means adapted to indicate the amount of force required to break the test piece.

4. Apparatus for testing concrete comprising a horizontal platform having a pair of upstanding supports for a test piece of concrete, one of said supports being disposed above one edge of the table and having a sharp upper edge parallel with said platform edge, means for securing the test piece upon said supports with one end of the test piece projecting beyond the said sharp-edged support, an upright bracket extending above said platform, a cross bar fixed to said bracket transversely of the test piece and approximately in the plane of the said edge of the platform, a horizontal lever extending longitudinally of the test piece and having its inner end extending over the test piece and under said cross bar, said bar having a bottom transverse member intermediate its ends engaging the upper side of the test piece near the end of its projecting portion and having a top transverse member near its inner end engaging the upper side of the test piece near the end of its projecting portion and having a top transverse member

5. Apparatus for testing concrete comprising a horizontal platform having a pair of upstanding supports for a test piece of concrete, one of said supports being disposed above one edge of the table and having a sharp upper edge parallel with said platform edge, the other support comprising a semi-spherical bearing with a plate resting on its upper surface as a support for a test piece of concrete; means for securing the test piece upon said support including a third support comprising a semi-cylindrical unit resting on a plate, one end of the test piece projecting beyond the sharp edged support, an upright bracket extending above said platform, a crossbar fixed to said bracket transversely of the test piece and approximately in the plane of the said edge of the platform, a semi-cylindrical bearing and a plate attached to the underside of said crossbar, a horizontal lever extending longitudinally of the test piece and having its inner end extending over the test piece and under said crossbar so that said inner end bears against said crossbar bearing a transverse member fastened to said lever intermediate, its ends engaging the upper side of the test piece near the end of its projecting portion and having a top transverse member

near its inner end engaging said crossbar in the manner above set out so that the lever is supported in horizontal position by said engagements, means connected with the free

5 end of the lever for depressing the lever to break the test piece and a measuring instrument associated with said depressing means

adopted to indicate the amount of force required to break the test piece.

In testimony whereof we affix our signatures.

ORREN HARDIN HANSARD.
